(57) **CLAIM**

The ornamental design for a loudspeaker rear cover, as shown and described.

DESCRIPTION

FIG. 1 is a perspective view of a loudspeaker rear cover showing our new design viewed from the right;

FIG. 2 is a top plan view thereof;

FIG. 3 is a side elevational view thereof;

FIG. 4 is another side elevational view thereof; and,

FIG. 5 is an enlarged cross-section view thereof taken along line 5-5 of FIG. 4.

The broken lines showing part of the loudspeaker rear cover and the remainder of the loudspeaker indicate unclaimed portions and form no part of the claimed design.
